(57) **CLAIM**

The ornamental design for a bath toy, as shown and described.

DESCRIPTION

FIG. 1 is a perspective view of a bath toy showing our new design;

FIG. 2 is a rear elevational view thereof;

FIG. 3 is a front elevational view thereof;

FIG. 4 is a side elevational view thereof; and,

FIG. 5 is a side elevational view thereof, opposite that shown in FIG. 4.

The broken lines are included for the purpose of illustrating portions of the bath toy that form no part of the claimed design, it being understood that the appearance within the unshaded portions of the bath toy likewise form no part of the claimed design.
